SPRING SEAT CONSTRUCTION

Stanley Overby, Inglewood, and Charles S. Viall,
Sr., Los Angeles, Calif.; said Viall assignor to
said Overby

Application October 15, 1943, Serial No. 506,328

2 Claims. (Cl. 155—50)

1

Our invention relates to spring seat construction comprising a platform supported by spring means upon a framework.

The principal objects of the invention are to provide an improved spring seat construction that will result in increased comfort and resilience, economy in manufacture, general superiority and serviceability, relative simplicity, inexpensiveness in construction and general efficiency.

The invention also comprises novel details of construction and novel combinations and arrangements of parts, which will more fully appear in the course of the following description. However, the drawings merely show and the following description merely describes embodiments of the present invention, which are given by way of illustration or example only.

Cross-reference is hereby made to an application for patent of Stanley Overby, Serial No. 569,018, filed December 20, 1944, on "Spring seat construction," which is a continuation in part of the present application.

In the drawings, like reference characters designate similar parts in the several views.

Fig. 1 is a plan view of an embodiment of our invention.

Fig. 2 is a side elevational view of Fig. 1, with portions of the frame broken away and partly in section.

Fig. 3 is an enlarged section taken on the line 3—3 of Fig. 1.

Fig. 4 is a face view, with a portion broken away, of the construction shown in section in Fig. 3.

Fig. 5 is an enlarged section taken on the line 5—5 of Fig. 1.

Fig. 6 is a perspective view of an alternative bracket construction.

Fig. 7 is an enlarged section taken on the line 7—7 of Fig. 2.

Fig. 8 is a side elevation of the construction shown in Fig. 7.

Fig. 9 is a side elevation, partly in section, of another form of the invention.

Fig. 10 is a horizontal section taken on the line 10—10 of Fig. 9.

Fig. 11 is an enlarged section taken on the line 11—11 of Fig. 10.

Fig. 12 is a still further enlarged transverse section taken on the line 12—12 of Fig. 11.

Fig. 13 is a broken, perspective view of a spring element together with portions of associated parts.

Fig. 14 is a broken, sectional view of a con-

2

struction combining the constructions of Figs. 2 and 9.

Referring more in detail to the drawings, the reference number 8 generally designates a framework of a chair or other seat. The framework comprises a front rail 10, a rear rail 12 and side rails 13. Arms are indicated at 14.

A platform 15 is supported within a spring steel frame 16. A fabric covering 17 is fastened within the frame 16 by any suitable means; coil springs 18 are suggested in the drawings. Hooks 19, looped around the frame 16, are hooked through the fabric 17 along the front of the seat covering 17. Similar hooks 19 are employed at opposite sides of the corners of the frame 16.

Also mounted within the frame 16 is a series of bent springs 20 hooked over the front and rear members of the frame 16. The springs 20 are preferably made of successive hairpin turns reversed with respect to each other, all the hairpin turns lying in a single plane. Coil springs 21 hook over the side members of the frame 16 and connect with loops in the turns of the springs 20, as shown in Fig. 1.

Abutting ends 22 of the frame 16 are encased in a ferrule 23. Flanges 24 and 25 on the ferrule are held together by lips 26 that are punched out of the flange 25, leaving openings 27. The lips 26 are passed through openings 28 in the flange 24 and are bent parallel with the flanges 24 and 25, as best shown in Fig. 3.

Front springs for supporting the frame 16 have helical loops 29 with legs 30 and 31 projecting tangentially from the helix. When at rest, the leg 30 is substantially horizontal and the leg 31 is upwardly inclined at an acute angle to the horizontal.

The outer end of the leg 30 is bent around a bearing 32 which is rotatably mounted upon a staple 33 driven into the back of the front rail 10. The bearing 32 may be made of compressed fibrous material impregnated with a lubricant such as graphite, so that the rotary connection between the bearing 32 and the staple 33 is lubricated at all times, preventing squeaking during use. It will be noted that the width of the bearing 32 is only slightly less than the distance between the legs of the staple 33 so as to substantially eliminate side motion of the bearing.

The rear portion of the frame 16 is supported by compound springs that have a lower coil 34 and upper coil 35 wound in opposite directions and connected by a substantially horizontal leg member 36. The lower coil 34 has a substantially horizontal, tangent leg member 37 that is bent at

55

right angles, as suggested at 38. The bent end 38 is maintained in a bracket 39. The bracket 39 comprises a back plate 40 and a front plate 41 with aligned screw openings 42. The front plate 41 has a channel whose members 43 and 44 are disposed substantially at right angles to each other, for respectively holding the leg 37 and the bent end 38 of the leg 37. This arrangement tends to prevent lateral turning or twisting movement of the lower coil 34.

The upper leg 45 of the spring 35 is disposed at an acute angle to the horizontal. The end of the leg 45 is bent substantially at right angles, as shown at 46. The leg 45 and its bent end 46 are firmly fastened to the frame 16 by means of clips 47 and 48 arranged substantially at right angles to each other at opposite sides of each rear corner bend in the frame 16 and at opposite sides of the angular bend connecting the leg 45 and its end 46.

The clips 47 and 48 are each formed of a single piece of resilient material bent upon itself. The clip 47 is bent to receive the frame 16 and the thereunder disposed leg 45, while the clip 48 is bent to receive the frame 16 and the thereunder disposed bent end 46. Flanges 49 and 50 depend from the bodies of the clips 47 and 48, with the flanges 49 gripping the bottom edges of the flanges 50, as best shown in Fig. 5.

It is believed clear to one skilled in the art, without further illustration or description, the upper legs 31 of the front coil springs 29 have bent ends similar to the bent ends 46, which extend along under the front member of the frame 16 and are held thereunder by clips 51 and 52 similar to clips 47 and 48. The bent ends of the legs 31 are thus fastened to each side of the front corners of the frame 16, in order to provide a substantially rigid connection of the spring ends with the frame 16, to avoid twisting or lateral play at such ends.

In the form shown in Figs. 9 to 13, a chair 60 has a base frame indicated at 55, which is supported upon legs 56. The base frame 55 has a front rail 57, a rear rail 58 and a middle rail 59.

A seat frame 61 of the chair 60 has front and rear rails 62 and 63 respectively. Suitable arms 64 and back 65 are mounted upon the seat frame 61.

Front coil springs 66 resiliently support the front of the seat frame 61 from the front rail 57. The upper arms 67 of the springs 66 have right angularly bent ends fixed in brackets 39, on the under side of the front rail 62 of the seat frame.

The lower arms 68 of the coil springs 66 have pivotal connections 69 with swivel arms 70. The arms 70 are flexible between the pivots 69 and loops 71 to permit the ends connecting with the pivots 69 to swing. The pivotal connections 69 operate on axes parallel with the front rail 57. The loops 71 of the swivel arms 70 engage grooved posts 72, which in turn are screwed to the front rail 57, as noted at 73. The posts 72 are mounted adjacent opposite sides of the base frame 55, as shown in Fig. 10.

Each side of the rear portion of the seat frame 61 is supported by oppositely wound coil springs 74 and 75 that are connected by a substantially horizontal arm 76. An upper arm 77 connects the upper coil 74 to a bracket 39 on the under side of the rear seat rail 63. An arm 78 connects the lower coil 75 with a bracket 39 on the top of the middle rail 59. It is to be under-

stood that the outer ends of the arms 77 and 78 have right angular bends that are engaged by the brackets 39, to prevent twisting of the spring supports, except inherent flexibility thereof.

5 The form in Fig. 14 is a combination of the forms shown in Figs. 2 and 9. In the form shown in Fig. 14 the platform 15 is supported at the rear by coils 34, 35 and by arms 36, 37 and 45, as in Fig. 2, but the front of the platform 15 is supported by springs 66, arms 68, 70, pivots 69 and posts 72, as in Figs. 9 and 10. The upper arm 31 of the coil spring 66, in Fig. 14, is the same as arm 31 in the form in Fig. 2 and the latter arm 31 is fastened to the frame 16 as described 10 in connection with Fig. 2.

The use of our invention is believed clear. The coil springs 21 resist lateral sway of the springs 20. The upper arms 31 and 45 are firmly held against twisting. The same is true of the 20 lower arm 37. The lower front arm 30 has an excellent swinging connection with the frame, by means of the bearing 32, which is continuously lubricated.

In the use of the form shown in Figs. 9 to 13, 25 the rear springs provide double coil support for the rear of the seat frame 61. The ends of the springs are likewise held against twisting, by the brackets 39. The lower arm 68 of the coil 66 may swing about the pivot 69, during vertical movements of the seat frame 61, due to the flexibility of the supporting arm 70. This enhances the vertical resiliency at the front of the frame. At the same time the arm 70 is free to swivel 30 around the post 72, permitting a lateral freedom of movement of the coil 66. This compound flexibility or movement about two axes at right angles to each other produces a very comfortable spring support.

40 While we have illustrated and described what we now regard as the preferred embodiments of our invention, the constructions are, of course, subject to modifications without departing from the spirit and scope of our invention. We, therefore, do not wish to restrict ourselves to the particular form of construction illustrated and described, but desire to avail ourselves of all modifications that may fall within the scope of the appended claims.

50 Having thus described our invention, what we claim and desire to secure by Letters Patent is:

1. In a seat construction, a framework, a frame for supporting a seat, resilient means supporting the frame on the framework, said means including spring elements each of which comprises two vertically disposed and oppositely wound coils having a horizontally disposed leg connecting the coils in laterally offset relation to each other, the upper coil having an upwardly inclined terminal leg extending from the upper coil and provided with an angular extension, and the lower coil having a terminal leg projecting in a direction substantially opposite to that portion of the terminal leg that stems from the upper coil, the terminal leg of the lower coil being provided with an angular extension, means clamping the first-named terminal leg and its therewith angular extension to the frame, and a channeled bracket for clamping the second terminal leg and its therewith angular extension to the framework to prevent vertical and rotative movement of said leg, to functionally interpose both coils in the spring support of the seat-supporting frame.

75 2. In a seat construction, a framework, a frame

for supporting a seat having corners, means supporting the frame on the framework including spring elements, each of which comprises upper and lower coils between said frame and framework and interconnected in offset relation to each other, the upper coil having a leg extending parallel with the sides of the frame and around a corner thereof, means to fasten said leg at the opposite sides of the corner of said frame, the lower coil having a leg extending in a direction opposite to the direction of said first mentioned leg and in parallel relation to the inside of the side rails of said framework, said last named leg provided with a bent end, and a bracket secured to the inner face of the rails, said bracket having a channel to receive a portion of the leg and the bent end thereof to prevent rotative movement thereof during flexing of the spring elements.
